UNITED STATES PATENT OFFICE.

JOHN D. ROBERTS, OF WILD ROSE, WISCONSIN.

BINDER ATTACHMENT.

949,911.

Specification of Letters Patent. Patented Feb. 22, 1910.

Application filed May 11, 1908. Serial No. 432,141.

To all whom it may concern:

Be it known that I, JOHN D. ROBERTS, a citizen of the United States, residing at Wild Rose, in the county of Waushara and State of Wisconsin, have invented certain new and useful Improvements in Binder Attachments, of which the following is a specification.

My invention relates to attachments to corn binders or the like, to prevent the ears being broken as they pass up the gathering boards. It is adapted for attachment to the inside fender rod and performs the same function as outside fender board. It is so constructed that it may be easily and cheaply manufactured; and can be connected to the binder with little difficulty.

In the drawings forming a part of this specification, and in which like symbols of reference represent corresponding parts in the several views: Figure 1 is a perspective view of a binder with the attachment in position; and, Fig. 2 is a side view of the device detached from the machine.

1 indicates the fender rod of the machine; 2 the attachment; and 3 a strap or the like having an eye encircling the fender rod and resting just below the bend in the fender rod. 4 is an eye formed from the strap 3. 5 is the outside fender board; and 6 bolts to connect the forward end of attachment to inner board.

7 is a hinge and 8 a pivot connecting the forward member of the hinge 7 to the bracket 9 to permit spring or give to the same.

The device may be made of sheet steel or wood, as desired.

The operation will be apparent from the foregoing. The inside fender board being lower than the outside board, and the long fender rod the same height as the outside fender board, the attachment on the rod is the same height and slant as the outside

board. The hinge on attachment allows the 45 rod to spring up and down while the pivot allows it to move right and left. The principle is to give the rod the same motion as if attachment was not on and is used to prevent the ears being torn or pulled off by the 50 rod, when the machine is in operation.

Having now fully described my invention, what I claim as new and desire to secure by Letters-Patent, is:—

1. In a harvester, the combination with 55 the gathering board and fender rod of the same, of a plate having a movable connection to the fender rod, and means connecting the plate with the gathering board so as to permit vertical and lateral play of the same. 60

2. In a corn harvester, the combination with the gathering board, of a fender rod mounted above the same, a plate connected to the fender rod, a bracket connected to the gathering board, and means connecting the bracket to the plate so as to permit vertical 65 and lateral movement of the latter.

3. In a corn harvester, the combination with a gathering board, of a fender rod supported above the gathering board, a plate, 70 a strap connected to said plate and having an eye to receive the fender rod, and means connecting the plate with the gathering board so as to permit vertical and lateral play of said plate. 75

4. In a harvester, the combination with the gathering board, of a fender rod mounted above the same, a plate connected to the fender rod, a bracket connected to the gathering board, and hinges connecting the 80 bracket to the plate so as to permit vertical and lateral play of the plate.

In testimony whereof I affix my signature in presence of two witnesses.

JOHN D. ROBERTS.
